UNITED STATES PATENT OFFICE.

SAMUEL M. KINTNER, OF PITTSBURGH, PENNSYLVANIA, ASSIGNEE TO WESTINGHOUSE ELECTRIC AND MANUFACTURING COMPANY, A CORPORATION OF PENNSYLVANIA.

BEARING-HOUSING.

1,138,666.

Specification of Letters Patent. Patented May 11, 1915.

Application filed March 2, 1910. Serial No. 546,855.

To all whom it may concern:

Be it known that I, SAMUEL M. KINTNER, a citizen of the United States, and a resident of Pittsburgh, in the county of Allegheny 5 and State of Pennsylvania, have invented a new and useful Improvement in Bearing-Housings, of which the following is a specification.

My invention relates to bearing housings 10 having waste oil reservoirs and it has special reference to those housings which are adapted for use with relatively high-speed dynamo-electric machines.

The object of my invention is to provide a 15 bearing housing which shall be of simple construction and shall effectively prevent the oil from being drawn from the oil thrower and drain opening and thrown upon the rotating member.

20 Heretofore, trouble has been experienced with relatively high-speed machines because of the tendency of their rotating members to create suctions of air from the overflow outlets of the waste oil reservoirs through the 25 bearing housings and drain openings. The difficulty has been that particles of oil were caught upon and carried with the air currents and deposited on the spiders of the rotating elements from which they worked 30 out into the cores and windings under the action of centrifugal force. In order to obviate this trouble, the bearing housing of my invention is so constructed that a passage of air through the oil catcher drain 35 opening is rendered impossible by means of an oil seal, as hereinafter described.

My invention has a further advantage 40 that it may readily be applied to housings already in use in which the above mentioned difficulty is experienced.

The accompanying drawings serve to 45 illustrate my invention, the single figure being a partially sectional elevation of a railway motor equipped with a bearing housing constructed in accordance therewith.

The bearing housing 1 of a railway motor 2, comprises a casting 3, the lower portion of which forms a waste-oil reservoir 4, having a drain 5 and an overflow outlet 6. A 50 tubular member 7 is fastened to the rim of the overflow outlet and projects into the reservoir a sufficient depth to form an ef-

fective seal. A drain opening 8 communicates between the oil catcher 9 and the waste-oil reservoir. The annular part 10 is an oil thrower which is fastened rigidly to the shaft 12 and serves to deliver the oil, which works out between the bearing 11 and the shaft 12, to the oil catcher and thence to the reservoir, thus preventing the oil from being thrown upon the motor armature. The laminated armature core 13 is provided with ventilating ducts 14 and is secured to the armature spider 15 in a well known manner, a plurality of air ducts 16 being provided for the circulation of air.

Previous to my invention, the current of air created by the revolving armature, through the overflow outlet, picked up drops of oil, in passing through the drain opening and past the oil thrower and catcher and deposited them upon the armature spider, from which they were thrown out through the ventilating ducts to the armature coils.

The effectiveness of my invention will be readily understood by those skilled in the art. It will also be evident that my invention may readily be applied to bearing housings already in use.

Although I have, for illustrative purposes, shown and described a specific structure of bearing housing as embodying my invention, I desire it to be understood that the details of the same may be modified without departing from the spirit and scope of my invention.

I claim as my invention:

1. A bearing housing comprising a cylindrical bearing, an oil-draining system, a waste oil reservoir having an overflow outlet 90 and a detachable tubular member which is secured to the edge of the overflow outlet and projects below the surface of the oil in the waste-oil reservoir.

2. A bearing housing comprising a cylindrical bearing, an oil-draining system, a waste oil reservoir having an overflow outlet, and a hollow shield or barrier projecting inwardly through the overflow outlet and into the oil in the reservoir, and means for detachably fastening the shield or barrier to the outer edge of said outlet.

3. A bearing housing comprising a cylindrical bearing, an oil-draining system, a

waste oil reservoir having an overflow outlet, a detachable curved pipe projecting inwardly through said outlet below the surface of the oil in said reservoir and having
5 an annular flange adapted to be seated against the outer edge of said outlet and means for securing said pipe thereto.

In testimony whereof, I have hereunto subscribed my name this 26th day of Feb., 1910.

SAMUEL M. KINTNER.
